UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITION-DYNAMO.

1,165,374.

Specification of Letters Patent. Patented Dec. 21, 1915.

Application filed July 29, 1913. Serial No. 781,840.

To all whom it may concern:

Be it known that I, CHARLES THOMAS MASON, a citizen of the United States, residing at Sumter, in the county of Sumter 5 and State of South Carolina, have invented certain new and useful Improvements in Ignition-DYNAMOS, of which the following is a specification, reference being had to the accompanying drawing.

This invention relates to dynamo machines, and particularly to those used for ignition purposes, and the object is to provide means whereby the intensity of the spark can be regulated so that it will not 15 become excessive at high speeds.

Ancillary objects are: to enable the intensity of the spark to be varied without varying the timing thereof in relation to the engine; and to increase the efficiency of the 20 apparatus in various ways which will be hereinafter pointed out.

My invention is illustrated in the accompanying drawing, in which the figure is a view partly in section, of a magneto embodying my invention.

Any form of magneto having a movable structure carrying the generating windings may be employed. Such a machine is disclosed in my pending application Serial 30 No. 782,681, filed November 21, 1912. As the details of construction of the magneto proper are immaterial, I shall describe the same sufficiently only to illustrate how the invention is practiced.

1 denotes a magnet in which is supported the movable armature structure 2 carrying the generating windings 3. The pole shoes 4 and 5 of this structure are subjected to magnetic impulses of alternately opposite polarity by means of a rotor revolving between them. Carried on the shaft of the rotor is the usual interrupter cam 6 which operates the movable contact member 7 of the interrupter mechanism, the insulated contact of which is shown in 8. This interrupter mechanism is carried in a casing 9 supported in such a way that it is movable about its support. To the armature structure 2 is attached the lever 10 by which the angular position of the field structure in relation to the rotor can be varied, as shown by the dotted lines. To the casing 9 is attached a suitable lever 11 by which the position of the casing in relation to the

armature structure may also be varied, as 53 shown by the dotted lines. Now in magnetos of this character, without the independently movable interrupter, the spark is of an intensity varying according to the timing. The timing is accomplished by moving 58 the structure carrying the winding and interrupter mechanism; hence if the magneto is driven at a high rate of speed as is often the case when used on motorcycles or racing automobiles, the spark is of such intensity that the spark plug points are fused, or heated to such a degree that pre-ignition results. This could be obviated by having the field structure stationary and moving only the interrupter mechanism as is done, 70 in the case of shuttle wound armature machines, but such an expedient results in a weakened spark at either the advance or retard position of the spark, depending upon the position of the interrupter in relation to the peak of the current wave. The range of timing is also limited. I accomplish the desired result by moving link 11 to advance or retard the interrupter mechanism, and, after the same is properly adjusted, thereby timing the ignition to the engine, I employ link 10 to move the armature or coil structure in relation to the rotor and the interrupter contacts so as to vary the intensity of the spark. This does 75 not alter the timing. Links 10 and 11 may be operated independently as just described, although a more convenient arrangement is to provide a common operating lever 12, which is fixed at one end 13, links 10 and 11 80 being relatively so attached that the field structure 2 is advanced ahead of the interrupter casing 9, so that while the interrupter casing advances say 12 degrees, the armature structure advances 15 degrees, the 85 spark being weakened in intensity by the difference in the relative position of the two members. When the links 10 and 11 are independently operative, it will be noted that the intensity of the spark may be varied 90 without varying the time thereof in relation to the engine, the intensity of the spark being regulated by the position of the armature structure controlled by link 10, while the timing is controlled by the 95 opening of the interrupter contacts carried by the casing 9, the position of which is controlled by link 11. Or when links 10

and 11 are connected to a common lever 12 the intensity of the spark is maintained the same for a given advance over a certain range at a given speed.

5 It is obvious to those skilled in the art that the lever 12 may be the ordinary advance and retard lever (or as it is commonly called the "spark lever") which is ordinarily used to control the position of the 10 interrupter casing 9 thereby varying the timing of the magneto. But with the type of magneto having a movable armature structure the timing lever would ordinarily be connected to the armature structure which 15 would also carry the interrupter casing 9 which would move with it. It will be seen, however, that my invention consists broadly of means for varying the timing of the generated wave of electromotive force and at 20 the same time varying the position of the interrupter mechanism in relation thereto, each means being movable independently of the other or both being movable together and bearing a determined relation to each 25 other for the purposes set forth.

Having thus described my invention what I claim and desire to secure by Letters Patent is—

1. An ignition dynamo comprising a fixed 30 primary field structure, an adjustable secondary structure carrying a generator coil, driven means for transferring the flux from the primary field to the secondary structure alternately, an interrupter controlling the 35 circuit of the generator coil, and means for differentially simultaneously adjusting the secondary structure and the interrupter, as and for the purpose intended, substantially as described.

40 2. An ignition dynamo comprising a fixed primary field structure, an adjustable secondary structure carrying a generator coil, driven means for transferring the flux from the primary field to the secondary structure alternately, an interrupter controlling the 45 circuit of the generator coil, and adjusting means for said secondary structure and interrupter with positive interconnections between said parts to produce a differential 50 rate of movement thereof, as and for the purpose intended, substantially as described.

55 3. An ignition dynamo comprising a fixed primary field structure, an adjustable secondary structure carrying a generator coil, driven means for transferring the flux from the primary field to the secondary structure alternately, an interrupter controlling the 60 circuit of the generator coil, and a lever for adjusting the said secondary structure and interrupter, with links connected to said parts at one end, and connected to separate points on the lever for differential movement thereby and therewith, as and for the purpose intended, substantially as described.

65 4. In an ignition dynamo, a primary

source of magnetomotive forces, an armature structure with a generating winding associated therewith, means for varying the flux from the primary source and reversing the same alternately through the armature 70 poles, an interrupter controlling the circuit of the generating winding, means for adjusting the relation between said armature structure and the primary magnetic source or flux transferring means, so as to time the 75 peak of the electromotive force wave and current wave in the winding, and associated means simultaneously actuated in the operation of the first means to adjust the interrupter toward or away from the peak of the 80 wave, to increase or diminish the relative intensity of the spark according to the direction of the adjustment.

5. The method of regulating the intensity 85 of the spark in an ignition system, which consists in producing a differential simultaneous adjustment of the time of current peak and the time of circuit interruption, as and for the purpose intended, substantially as described.

6. The method of timing the spark in 90 ignition systems, which consists in regulating the angular relation between the secondary or induced member of the system and the primary or inducing member; and 95 at the same time limiting the intensity by progressively and proportionately adjusting the point on the electromotive force wave or current wave at which discharge will take place.

7. The method of timing and regulating the sparking current in an ignition system, which consists in determining the time of maximum intensity by adjusting the relation 100 between the primary or inducing member and the secondary or induced member of a generating unit, and simultaneously determining the point of discharge, with relation to the point of maximum intensity, whereby the two may be made to diverge or coincide 110 at will.

8. In an ignition dynamo, an exciting field, a generating winding, a rotor by means of which flux from the exciting field is shifted in said generating winding to 115 produce electromotive-force waves, circuit controlling means associated with said generator winding adjustable to vary the time of a spark produced therefrom, and an adjustable device arranged to vary the relation between said exciting field and said generating winding to vary the timing of the produced electromotive-force wave, together with a positive differentially acting operating interconnection between said two 120 adjustable means.

9. In ignition apparatus for internal combustion engines, an electric generator having a member capable of adjustment for regulating the generator phases, shiftably 125

adjustable ignition controlling mechanism, means for shifting the said member within a range greater than the possible range of adjustment of the controlling mechanism, and means for adjustably shifting the controlling mechanism.

10. In ignition apparatus for internal combustion engines, an electric generator having a member capable of adjustment for regulating the generator phases, shiftably adjustable ignition controlling mechanism, means for adjustably shifting the said member at one rate of progression relatively to the engine, and means for shifting the controlling mechanism at a different progressive rate.

11. In ignition apparatus for internal combustion engines, an electric generator having a member capable of adjustment for regulating the generator phases, shiftably adjustable ignition controlling mechanism, means for adjustably shifting the said member at one rate of speed with respect to the engine, and means for shifting the controlling mechanism at a proportional differential progressive rate.

12. In ignition apparatus for internal combustion engines, an electric generator having a member capable of adjustment for regulating the generator phases, shiftably adjustable ignition controlling mechanism, means for shifting the said member within

a range greater than the possible range of adjustment of the controlling mechanism, and means for adjustably shifting the controlling mechanism at a rate proportional to the adjustable movement of the said member.

13. In ignition apparatus for internal combustion engines, an electric generator having a member capable of adjustment for regulating the generator phases, means for adjustably shifting the said member, shiftable ignition controlling mechanism including a contact actuating device movable upon adjustment of the said generator member, and means for also effecting shifting of the controlling mechanism.

14. In ignition apparatus for internal combustion engines, an electric generator having a member capable of adjustment for regulating the generator phases, shiftable adjustable ignition controlling mechanism, and common means for so adjustably shifting the said member and the controlling mechanism as to cause one to be moved at a predetermined rate of progression, and the other at a differential rate of movement.

In testimony whereof I hereunto affix my signature in the presence of two witnesses.

CHARLES THOMAS MASON.
